UNITED STATES PATENT OFFICE.

JOHN O. MILLER, OF CHICAGO, ILLINOIS, ASSIGNOR TO THE BRUNSWICK-BALKE-COL-
LENDER CO., OF CHICAGO, ILLINOIS, A CORPORATION OF DELAWARE.

DEVICE FOR CHALKING CUE TIPS.

Application filed July 9, 1927. Serial No. 204,594.

My invention relates to holders for billiard chalk.

One of the most important features of the game of billiards or pocket billiards is the proper chalking of the cue tip in order to prevent miscues. As far back as history of the game goes, there has never been any successful effort to improve the form in which billiard chalk has been made in order to facilitate the chalking of the tip, and to improve this most important feature of the game.

While there have been numerous inventions with reference to receptacles for holding the chalk, there has never been any successful effort devoted to devising new or improved methods with reference to the shape of the chalk which would make possible the improvement of this important feature of the game, or render it more facile for the player to properly chalk his cue so as to give best playing results.

The pieces of chalk heretofore in use are adequate for the purpose intended when they are first applied to cue tips, but as the depression in them becomes deepened by continual chalking it becomes necessary for the room-keeper to smooth down the chalk so that this hole is kept shallow, for if this is not done the player is unable to deposit a layer of chalk uniformly over the surface of the cue tip from the center to the side, and frequently the tip catches on the wall of the depression and is torn off. This necessitates additional labor and expense on the part of the billiard room owner in keeping his equipment in proper condition. Moreover, as the depression is deepened fragments of chalk are broken off at the sides which soil the hands of the player and are ground into the cloth, producing an unsatisfactory playing surface.

It is an object of my invention to ensure the even wear of the chalk and to prevent the formation of large holes therein. A further object of the invention is to provide means which will insure this even wear of the chalk without excessive wear upon or mutilation of the cue tip. This result is obtained by making the piece of chalk of approximately the diameter of a cue tip and mounting it snugly in a chamber in a holder of resilient construction, and which is preferably formed of material which will yieldingly retain the chalk and will yield sufficiently when engaged by the cue tip to prevent excessive wear

upon or mutilation of the latter. This facilitates the chalking of tips of different curvature and diameter even after the chalk has been used for some time, and the even wear of the chalk makes it possible to deposit an even layer over the active surface of the tip and to consume almost the entire piece so that wastage is reduced to a minimum.

The holder is formed so that it will expand or yield under any lateral movement of the cue tip when the latter is inserted in the bore. This is preferably accomplished by using a relatively soft and resilient material. Such a construction is particularly desirable, due to the fact that the holding chamber or cavity is of substantially the diameter of the cue tip. After substantial wear upon the chalk, the tip will be inserted in this cavity, and the use of a comparatively rigid or unyielding holder would tend to wear excessively or mutilate the cue tip, as the latter is moved within this cavity during the chalking operation and as the tip is withdrawn from the same.

Other objects and advantages of the invention will appear as the description proceeds.

Referring to the accompanying drawings, Figure 1 is a perspective view of a chalk holder embodying the invention, showing a cue tip applied to the chalk therein.

Figures 2 and 3 are a plan view and a central sectional view, respectively, of the holder, and

Figure 4 is a central sectional view of the holder showing the cue tip in elevation as applied to the chalk after the latter has been partially consumed.

The holder may be made of any desired material but a yieldable composition such as india rubber is preferred. It may be rectangular or of other desired shape, and has a substantially cylindrical chamber 2 therein in which a piece of chalk 3 snugly fits, the wall of the chamber gripping the chalk and preventing accidental displacement thereof. The piece of chalk has the shape of a disk and is of approximately the diameter of a cue tip 4. When fresh its exposed surface may be dished or indented as at 5 and it decreases in thickness as it is consumed. Figure 4 illustrates one stage in its consumption. Because of the small diameter of the piece of chalk, the cue tip does not make a deep hole in it. On the contrary, the wear on its exposed surface is substantially uniform

100

105

110

and an even coating is applied to the active surface of the tip.

It will be observed that the piece of chalk fits snugly in the chamber, which is of substantially the diameter of the cue tip. This snug fit resists movement of the chalk out of the chamber, and obviously, the resiliency of the material assists in holding the chalk in position. Furthermore, when the cue tip is inserted in the chamber, as illustrated in Figure 4, the yielding character of the holder avoids any danger of excessive wear upon or mutilation of the cue tip. Notwithstanding the snug fit of the cue tip in the cavity, as illustrated, any lateral movement of the cue tip will be accommodated by yielding of the holder, and hence the tip will not be torn from the cue.

Almost the entire piece of chalk may be used and the small part that is discarded may be readily removed from the holder and replaced by a new piece.

The invention is not limited to the specific details of construction of the modification illustrated and described, but may be embodied in diverse manners. For instance, the chalk may be somewhat tapered in shape.

A substantial range of equivalents is contemplated within the spirit of the invention and the scope of the appended claims.

I claim:

1. A cue chalking device comprising a holder of relatively soft resilient material having a cylindrical chamber of substantially the diameter of a cue tip and adapted to receive the latter snugly, a piece of chalk

having substantially the diameter of a cue tip snugly fitted in said chamber, the chamber having a transversely directed wall formed to support the piece of chalk against movement in one direction, the chalk being held by the close fit in the resilient material against movement through the open end of the chamber.

2. A cue chalking device comprising a resilient holder having a cylindrical chamber of substantially the diameter of a cue tip and adapted to receive the latter snugly, a piece of chalk having substantially the diameter of a cue tip snugly fitted in said chamber, the chamber having a transversely directed wall formed to support the piece of chalk against movement in one direction, the chalk being held by the close fit in the resilient holder against movement through the open end of the chamber.

3. A cue chalking device comprising a holder of relatively yieldable rubber having a cylindrical chamber of substantially the diameter of a cue tip and adapted to receive the latter snugly, a piece of chalk having substantially the diameter of a cue tip snugly fitted in said chamber, the chamber having a transversely directed wall formed to support the piece of chalk against movement in one direction, the chalk being held by the close fit in the yieldable material against movement through the open end of the chamber.

In witness whereof I have hereunto set my name.

J. O. MILLER.
